TYPE-WRITING MACHINE.

No. 851,847.

Specification of Letters Patent.

Patented April 30, 1907.

Application filed October 23, 1902. Serial No. 128,470.

To all whom it may concern:

Be it known that I, CHARLES W. WALKER, a citizen of the United States, and a resident of Bridgeport, in the county of Fairfield and State of Connecticut, have invented certain new and useful Improvements in Type-Writing Machines, of which the following is a specification.

My present invention relates to carriage feed or escapement mechanism for typewriting machines and the object of said invention is to provide simple, rapid and efficient mechanism of the character described.

To the above and other ends which will hereinafter appear my invention consists of the novel features of construction, arrangements of parts and combinations of devices to be hereinafter described and particularly pointed out in the appended claims.

In the accompanying drawings, wherein like reference numerals represent corresponding parts in the various views, Figure 1 is a vertical, front to rear, sectional view of one form of typewriting machine embodying my invention. Fig. 2 is an enlarged, detail, end view of the tension adjusting device for the dog rocker. Fig. 3 is an enlarged detail transverse, horizontal, sectional view of the same. Fig. 4 is an enlarged, detail, rear elevation of the feed dogs and a portion of the dog rocker. Fig. 5 is a fragmentary, side view, partly in section, of a portion of a type action and the escapement mechanism controlled thereby. Fig. 6 is an enlarged, detail, vertical, sectional view of a portion of the escapement mechanism. Fig. 7 is an enlarged, detail, bottom view of the escapement wheel and certain of the associated parts. Fig. 8 is a plan view of the same. Fig. 9 is a transverse, sectional view of a portion of the dog rocker, the section being taken on the line $x-x$ of Fig. 4. Fig. 10 is an enlarged, detail, fragmentary, perspective view of the dog rocker.

The invention is shown applied to a typewriting machine of the character illustrated in my application filed December 21, 1901, Serial No. 86,821, and in the application of Arthur W. Smith filed December 11, 1901, Serial No. 85,451, and certain of the features shown herein are claimed in said applications. It should be understood, however, that the carriage feed or escapement mechanism of my present invention may be applied to various characters of writing machines.

The frame 1 of the machine supports oppositely grooved tracks 2 that receive anti-friction balls 3 which are likewise received in oppositely grooved tracks 4 of the carriage 5, the latter being provided with a traction roller 6 that bears upon a track 7 and a platen 8 is carried by and adapted to rotate in bearings in the carriage. Projecting rearwardly from the carriage 5, and extending throughout the length thereof, is a feed rack 9 which meshes with the pinion 10 operatively connected to the escapement mechanism, as will hereinafter more clearly appear. Each of the finger keys 11 has a key stem 12 that is pivoted at 13 to a link 14 pivoted on a cross rod 15 that extends from side to side of the machine.

The lower end of each key stem is pivoted at 16 to a curved crank arm 17 secured to a lever 18 pivoted at 19 on a fixed bar that extends from side to side of the machine. The lower end of each lever 18 is connected at 20 to a draw link 21 that in turn is pivoted at its opposite end 22 to one arm of a bell crank lever 23, the other arm of said lever being pivoted at 24 to an upright draw link 25. Each bell crank lever 23 is pivoted at 26 to a hanger 27, the various hangers 27 being arranged in two oppositely disposed segmental series. The upper end of each upwardly-extending link 25 is connected at 28 to a driver 29 or lever pivoted on a curved pivot rod 30 supported by a type ring 31. The lower end of each driver is connected by a pivot 32 to one member 33 of a jointed type bar, the two members 33 and 34 of each bar being pivotally united at 35. The section 34 of each jointed type bar has a bearing disk 36 at one end thereof which is received within a channel bearing formed by two oppositely disposed plates 37 with peripheral channel grooves near the edges thereof for the reception of the bearing portions 36 of the various type bars, the plates themselves being supported by an upward extension 38 projecting from the frame 1 of the machine. The types 39 on the various type bars normally rest against an inking pad 40, as illustrated in Fig. 1, and a depression of a key is effective to move the associated type to the printing point as shown in Fig. 5 and a spring 41 is provided for each action, one end of said spring being connected to the associated link 25 and the opposite end thereof to the driver

29 so that when the pressure on the finger key is released, the spring 41 is effective to restore the parts to the normal positions. Situated above the plates 37 is a universal 5 plate 42 that has a depending peripheral flange 42^a and which is so arranged that the plate will be tilted or one side thereof elevated, by the contact of a member 34 of the jointed type bar, when a finger key is de-
10 pressed and the type is moved to the printing point as shown in Fig. 5. The movement thus transmitted to the universal plate 42 is effective to elevate a rod 43 that is provided with a head 44 which bears on the upper side 15 of the plate 42, whereas the rod itself passes loosely through a central opening in the plate and through a central opening in the upward extension 38 of the frame 1. The lower end of this rod 43 passes through an opening in a 20 block 45 and an adjustable nut 46 is received on the threaded end of the rod below said block. The block 45 is connected by a knuckle joint to an arm 48 that projects forwardly from the dog rocker, the pivot of the 25 joint being indicated at 47, and the construction is such that the arm 48, together with the dog rocker, is adapted to receive a movement independently of that transmitted thereto by the universal plate, as will herein-
30 after more clearly appear. The dog rocker or carrier comprises the forwardly extending arm 48, hereinbefore referred to, a downwardly extending arm 49 and a rearwardly extending arm 50. The downwardly ex-
35 tending arm carries in a slot therein, a link 51 pivoted at 52 and adapted to abut against a laterally extending pin 53 carried by the arm 49 and projecting across the slot therein, so as to cause the dog rocker to be moved with
40 the link when the latter is moved toward the front of the machine, but which permits a movement of the dog rocker independently of the link. The lower end of the link 51 is pivoted at 54 to a forwardly extending draw link 55, the front end of which is pivoted at 56 to one arm of a bell crank lever 57, the other arm of said lever being pivoted at 58 to a key stem 59 provided with a spacing bar or key 60 having depending ears to which are
45 pivoted the forward ends of links 61 that are united by a cross bar 61^a and the rear ends of which are pivoted at 62 on a cross bar that extends from side to side of the machine. By these means motion may be transmitted
50 to the dog rocker from the spacing bar without affecting the universal plate.
The dog rocker has a shaft 63 rigidly connected thereto by a set screw 64, said rock shaft being seated in side bearings 65 that
60 constitute portions of bracket plates 66 secured to the frame of the machine. Upon reference to Fig. 3, it will be seen that the hub 67 of the dog rocker has a housing 69 secured thereto by screws 68 and that this
65 housing is provided with bearings 70 (Fig. 2)

for a worm 71, one end of which extends through a bearing 70 in the housing and is provided with a notched head 72 by means of which the worm can be turned by a screwdriver or like tool. Contained within the 70 housing 69 and loosely mounted on the shaft 63, is a worm wheel 73 that is engaged by the worm and may be turned thereby. A coiled spring 74 surrounds the shaft 63 and one end of said spring is connected at 75 to the worm 75 wheel 73, whereas the opposite end of the spring bears against a pin 76 that projects from one side of a bracket plate 66 (Fig. 10). Thus the coiled spring 74 constitutes a restoring spring for the dog rocker and the 80 worm 71 affords means for adjusting the worm wheel 73 in order to vary the tension of the spring of the dog rocker.

The rearwardly projecting arm 50 of the dog rocker has an upwardly and rearwardly 85 extending arm 77 that supports a bearing 78 through which a vertically disposed so-called fixed dog 79 passes. This fixed dog is adjustably secured in place by a set screw 80 that passes through a threaded opening in 90 the side of the bearing 78, and the inner end of said screw bearing against the fixed dog 79 secures it in the adjusted position. Depending from the arm 50 is a bearing 81 that is apertured fore and aft of the machine for the 95 reception of one arm 82 of a loose L-shaped feed dog 83, the other arm 84 constituting the feed dog proper. The forward end of the pivotal arm of the loose dog is likewise received in an opening in the depending arm 49 100 of the dog rocker and which constitutes an additional bearing therefor. A sleeve 85 is secured by a set screw 86 to the pivot arm of the loose dog forward of the bearing 81 so as to maintain the dog against displacement 105 from its bearings. A coiled spring 87 surrounds the pivot arm of the loose dog and is connected at one end to the depending arm 49 of the dog rocker, whereas the other end of said spring is connected to the collar or sleeve 110 85. The set screw 86 affords means for securing an adjustment of the collar around the pivot arm of the loose dog so that the tension of the spring 87 thereon may be varied at will. The rearwardly directed arm 115 50 of the dog rocker has a barrel-like portion 88 formed thereon and this barrel-like bearing portion is slotted transversely at 89 for the reception of a plate 90 which is adapted to be adjusted along said slot.

Oppositely disposed adjusting screws 91 are received in tapped openings in the ends of the barrel-like portion 88 and the inner coned ends of said screws bear against diagonal shoulders 92 on the plate, thus preventing 125 the plate from being withdrawn from the slot and at the same time providing means whereby the plate may be shifted or adjusted in the slot and transversely of the rocker. The rearwardly extending portion of the 130

plate 90 is bifurcated at 93 for the reception of the upright arm 84 of the loose feed dog, the arms 94 formed by the bifurcation, constituting stops which limit the vibration of the loose feed dog in opposite directions.

The vertically arranged feed dogs are oppositely disposed and are situated upon opposite sides and transverse to the plane of a horizontally disposed escapement wheel 95 which is preferably in the form of a disk with a circular series of round escapement openings 96 extending therethrough and located within the periphery of the disk. These enclosed openings, apertures or holes are equidistant and are of such an extent that narrow webs 97 are formed between them. While the feed or escapement wheel 95 is preferably formed as a disk in the manner described, it should be understood that it may be formed integral with its carrier 98. When the escapement wheel is formed in the nature of a disk, I prefer to provide a series of locking apertures or slots 99 therein for the reception of similarly located studs 100 on the carrier so that when the escapement wheel is placed in position on the carrier with the studs 100 projecting in the apertures 99, the escapement wheel will be located to rotate with its carrier. The cylindrical portion 101 of the carrier may be threaded on its outer surface for the reception of a nut 102, which when screwed in place as illustrated in Fig. 6, bears on the escapement wheel and maintains it against displacement from its carrier. By this construction, means are provided by which an escapement wheel of one character or spacing may be readily replaced by another escapement wheel of a different character or spacing.

The carrier 98 has a depending hollow stem 103 that extends through a sleeve 104 contained within an opening in the frame 1 of the machine. The lower end of the hollow stem 103 receives a collar 105 that is secured in place by a set screw 106 which is received in a threaded opening in the collar and bears at its inner end against the hollow stem to maintain the collar in place and thus prevent the carrier from being displaced from its bearing. The upper portion of the carrier has a channel or groove 107 therein for the reception of anti-friction balls 108 and these balls likewise co-operate with a bearing formed at the upper edge of the sleeve 104 so that a ball bearing support is provided for the carrier and the escapement wheel secured thereto. A split ring or washer 109 may be seated in and secured to the carrier beneath the channel 107 for the balls by the pressure thereof so as to retain the balls in the carrier 98 when the parts are being assembled and to prevent dust or grit from entering the bearings. The upper end of the support 98 is provided with a series of crown 65 ratchet teeth 110, which co-operate with

suitable clutch mechanism contained within the housing 111 and the purpose of which is to operatively connect the escapement wheel to the shaft or sleeve 112 that rotates with the pinion 10, so that when the escapement mechanism is actuated, the carriage under the tension of the usual carriage spring (not shown) will be moved a letter space distance at a time in the direction of its feed and whereby the carriage may be returned or moved from left to right without transmitting motion to the escapement wheel. The clutch mechanism contained within the housing 111 is essentially the same as that shown and described in my application above referred to and which is also shown in British Patent No. 25,382 of 1901 to the Yost Writing Machine Company.

From an examination of Fig. 4, it will be observed that in the normal positions of the parts the feed dogs are directed toward each other and toward the interposed escapement wheel and that said dogs are in substantial alinement and are presented end to end. When a finger key is depressed, motion will be transmitted to the jointed type bar and the member 34 thereof will, in the movement of the type to the printing point, contact with the universal plate, thereby tilting it, which results in the bar 43 being elevated to raise the arm 48 of the dog rocker as indicated in Fig. 5. The effect of this movement is to turn the dog rocker with its shaft 63 so as to move the loose dog out of engagement with the escapement wheel and to simultaneously carry the fixed dog into the same opening that contained the loose dog, as represented in Fig. 5. The loose dog having been moved clear of the escapement wheel in the manner stated, will be moved on the dog rocker around its pivotal center by the spring 87 so that the end of the loose dog 64 will swing to a position opposite the next opening *a* in the escapement wheel, as represented diagrammatically and in dotted lines in Fig. 8. When the pressure on the finger key is released, the dog rocker will be restored to its normal position by the spring 74 and the loose dog will be projected into the opening *a* and will first be brought into contact with that portion of the wall of said opening which is nearest the periphery of the escapement wheel and which is indicated at *b*. The same rocking movement of the dog rocker is effective to withdraw the fixed dog from the opening *c* into which it was projected and the pressure exerted by the carriage spring will tend to rotate the escapement wheel, through the feed rack 9 and the intermediate connections between the rack and escapement wheel, thus pressing the loose dog back to the normal position or into alinement with the fixed dog and to the position represented in full lines in Fig. 8, and also in Fig. 4, where it is arrested by one of the stops, 130

thereby affording a letter feed movement of the carriage. Upon reference to Fig. 8, it will be understood that the loose dog swings in a plane transverse to the plane of the escapement wheel and which is represented by the line *d* in Fig. 8. It will likewise be seen that in the movement of the loose dog to the advanced position as from the opening *c* to the opening *a* in the escapement wheel it first contacts at *b* with the curved side wall of the aperture *a* and as the loose dog moves with the escapement wheel after being engaged thereby, said dog is gradually moved from the position indicated in dotted lines in Fig. 8 to that indicated in full lines, and assumes a different relative position in the aperture or opening. Thus when the loose dog first engages the wall of an opening in the escapement wheel, it is nearest the periphery thereof and is gradually moved toward the center of rotation of the wheel as the wheel and dog move to the position where the dog and escapement wheel are arrested against further rotation by one of the stops 94. By this construction I am enabled to provide a simple, rapid and efficient escapement or carriage feed mechanism wherein the escapement wheel can be made very thin and light without decreasing the strength or rigidity of the wheel and at the same time increasing the efficiency thereof. Thus by providing a series of openings in the escapement wheel, as shown, which are contained within the periphery thereof, I am enabled to make the wheel of a comparatively thin disk with but little space between the openings at those portions 97 of the intervening webs where the "let off" takes place, thereby providing a quick action of the escapement without decreasing the strength of the escapement wheel. This latter result is due to the fact that the webs between the openings not only receive support from the central portion of the wheel but the peripheral portion thereof extends around the openings and constitutes an integral portion of the webs and lends additional support thereto and they are only made thin between the openings at the portions 97 where it is essential that they should be made thin in order to secure a rapid operation of the escapement, and a strong and rigid structure nevertheless is provided wherein there is little liability of the webs being broken. Furthermore, by reason of the loose dog contacting with a sloping or curved wall of the aperture when it springs to the advanced position, or where it first engages in the next on-coming aperture in the escapement wheel, as represented in dotted lines in Fig. 8, I avoid the usual objectionable clicking noise that takes place in the ordinary escapement mechanism and provide an escapement wherein the noise is wholly avoided or is re-

duced to a minimum. Furthermore it will be observed that the movement of the loose dog on the rocker and the movement of the dogs with the rocker are in directions transverse to the plane of the escapement wheel and that it requires a very slight movement of the parts to effect the alternate engagement and disengagement between the dogs and the escapement wheel; that a movement of the dogs in a general direction in which they extend, and at substantially right angles or transverse to the plane of the escapement wheel, takes place when the dog rocker is vibrated on its horizontally disposed pivotal axis; that the pivotal axis of the loose dog is substantially horizontal and is directed fore and aft of the machine and at right angles to the pivotal axes to the dog rocker and escapement wheel and parallel to the plane of the escapement wheel and that the said pivotal axis of the loose dog is radially directed with relation to the escapement wheel or that the dog may swing in a plane *d* which is at substantially right angles to a plane radiating from the center of said wheel and that the pivotal axis of the dog rocker is at right angles to the vertically disposed pivotal axis of the escapement wheel.

The action of the escapement mechanism may be nicely determined and regulated by the set screws 80 and 91, the former providing a vertical adjustment of the fixed dog, whereas the latter provides an adjustment of the stops for the loose dog, to limit the independent movement thereof in opposite directions.

What I claim as new and desire to secure by Letters Patent, is:—

1. In escapement mechanism for typewriting machines, the combination of an escapement wheel having a series of escapement holes located inside of the periphery thereof, and an escapement device co-operating therewith.

2. In carriage feed mechanism for typewriting machines, the combination of an escapement wheel having a series of circularly arranged escapement apertures extending therethrough, each aperture having a wall that entirely surrounds it, and an escapement device that co-operates with said wheel.

3. In a typewriting machine, the combination of a carriage, an escapement wheel operatively connected thereto, said escapement wheel having a series of inclosed escapement openings therein that are spaced at equal distances apart, and feed dogs which co-operate with said escapement wheel at the escapement openings therein.

4. In a typewriting machine, the combination of a carriage, an escapement disk operatively connected thereto, said escapement disk having a circular series of escapement apertures located inside of the periphery thereof, and feed dogs which co-operate with

said escapement disk at the escapement openings therein.

5. In carriage escapement mechanism for typewriting machines, the combination of an escapement wheel having a series of round escapement openings therein, and feed dogs which co-operate with said escapement wheel at said escapement openings.

6. In a typewriting machine, the combination of a carriage, an escapement disk operatively connected thereto, said disk having a circular series of round openings located within the periphery thereof, and feed dogs which co-operate with said escapement disk and are adapted to extend into the openings therein.

7. In a typewriting machine, the combination of a carriage, a removable escapement disk operatively connected thereto, said disk having a circular series of round openings located within the periphery thereof, and feed dogs which co-operate with said escapement disk and are adapted to extend from opposite directions into the openings therein.

25 8. In carriage feed mechanism for typewriting machines, the combination of a feed wheel having a series of openings therein located within the periphery of said feed wheel and feed dogs that extend from opposite directions transverse of the plane of the feed wheel and which are adapted to be alternately projected into the openings therein.

9. In a typewriting machine, the combination of a carriage, an escapement wheel operatively connected thereto and having a circular series of openings that are located within the periphery of said wheel, a loose feed dog that is located to one side of the plane of said wheel, a fixed dog that is located on the other side thereof, and means for moving said dogs alternately into and out of the openings in the escapement wheel.

10. In a typewriting machine, the combination of a detachable escapement wheel having a circular series of feeding openings located within the periphery of said wheel, a co-operating fixed dog or detent, a co-operating loose or stepping dog, adjustable means for limiting the throw of the loose dog, and means for affording the substitution of one escapement wheel for another, whereby an escapement wheel with one character of spacing may be replaced by an escapement wheel with a different character of spacing.

55 11. In carriage escapement mechanism for typewriting machines, the combination of an escapement wheel having a series of openings located within the periphery of said wheel and co-operating feed or escapement dogs, the ends of which are directed toward each other and toward the interposed escapement wheel, means for vibrating said dogs in the directions in which they are directed, and means for affording an independent vibration of one of said dogs.

12. In a carriage escapement mechanism for typewriting machines, the combination of an escapement wheel having a circular series of escapement openings within the periphery thereof, a dog rocker, a fast dog or detent and a loose stepping dog carried thereby, the said dogs projecting toward each other and adapted to pass into the escapement opening from opposite sides of the wheel, the loose stepping dog being mounted to swing independently of its rocker in a plane that is at substantially right angles to the plane of the escapement wheel, the loose dog being moved to normal position in the last mentioned direction by the escapement wheel.

70 13. In a carriage escapement mechanism for typewriting machines, the combination of an escapement wheel having a series of openings therein, which escapement openings are located within the periphery of said wheel, a dog rocker, a fast dog and a loose dog carried thereby, the loose dog being mounted to swing independently of its rocker in a plane that is substantially at right angles to the plane of the escapement wheel, the loose dog being moved to normal position in the last mentioned direction by the escapement wheel.

75 14. In a carriage escapement mechanism for typewriting machines, the combination of an escapement wheel having a circular series of escapement openings located within the periphery thereof, a dog rocker, a fast dog and a loose dog carried by said rocker and projecting toward each other and toward the interposed escapement wheel, the said loose dog being mounted to swing independently of its rocker in a plane that is substantially at right angles to the plane of the escapement wheel, the loose dog being moved to normal position in the last mentioned direction by the escapement wheel.

80 15. In a typewriting machine, the combination of a carriage, a horizontally disposed escapement wheel operatively connected thereto, a dog rocker which has a horizontal pivot and vertically disposed feed dogs that are carried by said dog rocker and co-operate with the escapement wheel, and which are located on opposite sides of the horizontal plane in which the escapement wheel is situated, one of said dogs being a loose stepping dog that moves on a horizontal pivot which extends at right angles to the pivot of the dog rocker and is parallel to the plane of the escapement wheel.

85 16. In a typewriting machine, the combination of an escapement wheel, a co-operating fixed dog, a co-operating substantially L-shaped loose stepping dog, one arm of which constitutes a pivot for the dog, whereas the other arm constitutes the dog proper, said dogs being oppositely disposed and projecting endwise toward the interposed escapement wheel.

90 17. In a typewriting machine, the combination

nation of an escapement wheel, a dog carrier, a fixed dog adjustably secured to said dog carrier, and an oppositely disposed loose dog, said dogs being directed toward each other and toward the interposed escapement wheel.

18. In a typewriting machine, the combination of a carriage, a horizontally disposed escapement wheel with escapement openings within the periphery thereof, a dog rocker, and oppositely disposed vertically arranged feed dogs carried by said rocker, and one of which is a pivoted loose dog with the pivot thereof extending fore and aft of the machine.

19. In a typewriting machine, the combination of a carriage, a horizontally disposed escapement wheel having a circular series of openings arranged within the periphery of the wheel, a dog rocker and oppositely disposed vertically arranged feed dogs carried by said rocker and extending on opposite sides of the escapement wheel, and one of which is a pivoted loose dog with the pivot thereof extending fore and aft of the machine.

20. In a typewriting machine, the combination of an escapement wheel, a carrier therefor and to which said wheel is firmly attached and removably secured, roller bearings for said carrier, and feed dogs which co-operate with said escapement wheel.

21. In a typewriting machine, the combination of an escapement wheel having a circular series of openings located within the periphery of said wheel, a carrier to which said escapement wheel is removably secured, and oppositely disposed feed dogs which co-operate with the escapement wheel.

22. In a typewriting machine, the combination of an escapement wheel having a circular series of round openings located within the periphery of said wheel, a carrier to which said escapement wheel is removably secured, roller bearings for said carrier, and oppositely disposed feed dogs which project toward each other and toward the interposed escapement wheel.

23. In a typewriting machine, the combination of an escapement wheel having a circular series of openings therein, and co-operating feed dogs, one of which is a loose dog that is vibrated into and out of said openings and first contacts with a wall of an opening nearest the periphery of the wheel and gradually moves along said wall toward the center of the wheel, as the wheel is brought to rest by said loose dog.

24. In a typewriting machine, the combination of a carriage, an escapement wheel operatively connected thereto and having a circular series of round openings therein, and co-operating feed dogs located upon opposite sides of said wheel and projecting toward each other and toward the interposed escapement wheel, the end of one dog extending to-

ward the end of the other when the parts are in the normal positions and one being a loose dog that is adapted to vibrate transversely of the plane of the escapement wheel in the movement of the dog from one opening toward the next opening in the wheel.

25. In a typewriting machine, the combination of a carriage, an escapement wheel, operatively connected thereto and having a circular series of round openings therein, a dog carrier, feed dogs carried by said carrier and located upon opposite sides of said wheel and projecting toward each other and toward the interposed escapement wheel, the end of one dog extending toward the end of the other when the parts are in the normal positions, and one being a loose dog that is adapted to vibrate in a direction transverse to the plane of the escapement wheel in the movement of the dog from one opening toward the next opening in the wheel, and means for vibrating said dog carrier so as to move the dogs in the general direction in which they extend when in the normal positions.

26. In a typewriting machine, the combination of a carriage, a horizontally disposed escapement wheel operatively connected thereto and having a circular series of round openings therein, a horizontally pivoted dog carrier, vertically disposed feed dogs carried by said carrier and located upon opposite sides of said wheel and projecting toward each other and toward the interposed escapement wheel, the end of one dog extending toward the end of the other when the parts are in the normal positions and one being a horizontally pivoted loose dog that is adapted to vibrate in a direction transverse to the plane of the escapement wheel in the movement of the dog from one opening toward the next opening in the wheel, and means for vibrating said dog carrier on its horizontal pivot so as to move the dogs in a general vertical direction and in the direction in which they extend when in the normal position.

27. In a typewriting machine, the combination of a carriage, an escapement wheel operatively connected thereto and having a circular series of openings therein, a dog carrier, a fixed dog adjustably secured to said carrier, a loose substantially L-shaped dog, one arm of which constitutes a pivot that the dog swings on, whereas the other arm constitutes the dog proper, said dogs being on opposite sides of the escapement wheel and directed toward each other and toward the interposed escapement wheel, and means for vibrating said carrier so as to move the dogs at substantially right angles to the plane of the escapement wheel.

28. In a typewriting machine, the combination of a carriage, an escapement wheel operatively connected thereto and having a circular series of openings therein, a dog car-

rier, a fixed dog carried by said carrier, a loose substantially L-shaped dog, one arm of which constitutes a pivot that the dog swings on whereas the other arm constitutes the dog proper, a spring that surrounds the pivot arm of said loose dog and tends to maintain it out of alinement with the fixed dog and to swing it in a direction transverse to the plane of the escapement wheel, said dogs being on opposite sides of the escapement wheel and directed toward each other and toward the interposed escapement wheel, and means for vibrating said carrier so as to move the dogs at substantially right angles to the plane of the escapement wheel.

29. In a carriage escapement mechanism for typewriting machines, the combination of a dog rocker, a fixed dog carried thereby, an L-shaped loose stepping dog, one arm of which constitutes a pivot on which said dog swings whereas the other arm constitutes the loose dog proper, a spring connected to said pivot arm of the loose dog and to dog rocker, means for adjusting the tension of said spring, and a co-operating escapement wheel.

30. The combination with a dog rocker, of a housing secured thereto, a worm mounted in bearings in said housing, a co-operating worm wheel contained within said housing, and a coiled spring which is connected at one end to the worm wheel and at the opposite end to a fixed portion of the machine.

31. The combination with a dog rocker and rock shaft therefor, of a housing secured to said dog rocker, a worm mounted in bearings in said housing, a co-operating worm wheel contained within said housing and loosely mounted on the shaft of the dog rocker, and a coiled spring which surrounds said shaft and is connected at one end to the

worm wheel and at the opposite end to a fixed portion of the machine.

32. In escapement mechanism for typewriting machines, the combination of a dog rocker, a bifurcated plate carried by said dog rocker, means for adjusting said plate relatively to the dog rocker, and a loose dog carried by the dog rocker and extending into the bifurcation in said plate.

33. In escapement mechanism for typewriting machines, the combination of a dog rocker, a bifurcated plate seated in a groove in said dog rocker, adjusting screws that co-operate with said plate to maintain it in said groove and to afford an adjustment of said plate relatively to the dog rocker, and a loose dog carried by the dog rocker and extending into the bifurcation in said plate and limited in its vibration by the plate.

34. In escapement mechanism for typewriting machines, the combination of a dog rocker, a bifurcated plate that is seated in a groove in said rocker, adjusting screws that project in opposite directions and bear against said plate to maintain it in its groove and to afford an adjustment thereof along its groove and relatively to the dog rocker, and an L-shaped loose dog that has one arm which extends into the bifurcation in said plate and which is limited in its movement thereby.

Signed at the borough of Manhattan, city of New York, in the county of New York and State of New York this 21st, day of October A. D. 1902.

CHARLES W. WALKER.
